ATOMIZING NOZZLE

Joseph T. Voorheis, Oakland, Calif.

Application July 15, 1941, Serial No. 402,482

3 Claims. (Cl. 299—120)

This invention relates to an atomizing nozzle for oil burners and like apparatus.

The object of the present invention is generally to improve and simplify the construction and operation of atomizing nozzles; to provide an atomizing nozzle which is simple and cheap to manufacture, which may be readily taken apart, and in which all flow passages are accessible for cleaning in the event of carbon formation or stoppage of the passages; and further, to provide an atomizing nozzle which is efficient in use and which insures atomizing of the oil or fuel employed under varying operating pressures.

The atomizing nozzle is shown by way of illustration in the accompanying drawing, in which

Fig. 1 is a central vertical longitudinal section of the atomizing nozzle;

Fig. 2 is an end view of the nozzle;

Fig. 3 is a cross section taken on line III—III of Fig. 1; and

Fig. 4 is a cross section taken on line IV—IV of Fig. 1.

Referring to the drawing in detail, and particularly to Fig. 1, A indicates a tube which is connected with a source of fluid supply under pressure. Secured to the forward end of the tube is a fitting 2 which is hexagonal-shaped in cross section. This fitting may be welded to the tube A, as shown at 3, or otherwise secured. It has an extension 4 which extends into the tube A, and another extension 5 which is threaded on the exterior, as indicated at 6. Positioned forwardly of the fitting 2 is a head member B. Formed on the rear end thereof is a longitudinally extending chamber 7, the interior of which is threaded to permit the head A to be screwed onto the threaded extension 5. Formed in the forward end of the head member B is a chamber having a reduced portion which is interiorly threaded as shown at 8, and an enlarged portion indicated at 9. Drilled from the rear of the head, or otherwise formed, are a plurality of longitudinally extending passages 10. Their forward ends terminate and communicate with the enlarged chamber 9, while their rear ends open through the rear of the head but are normally closed when the head is screwed onto the extension 5. Drilled on an angle from the rear chamber 7 to communicate with the passages 10 are forward passages 11. These passages convey oil or similar fluid passing through the tube A, and a central passage 2a formed in the fitting 2. The fluid then flows into the chamber 7 and the passages 11, and then into the passages 10, and as these communicate with

a large chamber 9, fluid under pressure will be delivered thereto.

An atomizing nozzle is provided which cooperates with the head B. This nozzle is generally indicated at C. It has a head portion and a reduced threaded extension 12 which is screwed into the threaded reduced portion 8 of the front chamber. A longitudinal passage 14 is formed in the atomizing nozzle, and this terminates in a discharge orifice 15 at the forward end. The rear side of the head is bevelled, as at 16, and engages a similar seat 17 formed at the front of the head, thus sealing or closing the forward end of the head when the atomizing nozzle is screwed into place.

The diameter of the extension 12 is such that an annular chamber is formed between the extended portion of the atomizing tip and the enlarged chamber 9, and it is into this chamber that the fluid or oil is delivered by the longitudinally extending passage 10. Tangentially arranged inlet passages 18 are drilled in the atomizing nozzle, and these communicate with the interior passage 14 and with the discharge orifice 15, and as a pin 19 secured in the head A extends into the passage 14, the rear end of the passage 14 is closed and a chamber is formed in which the oil or fluid entering through the tangentially arranged ports swirls or rotates at high velocity before discharging into the orifice 15. Thus when the swirling fluid or liquid discharges, it is atomized and a high efficiency of combustion is maintained, as the proper amount of air is admitted.

In actual practice, the tube A may be supported in any suitable manner, and, as previously stated, is connected with the source of fluid under pressure, such as hot oil or the like. A tube 20 usually surrounds the tube A and the atomizing nozzle as is standard practice, but this merely serves as a guide and a shield for the tube A and the atomizing nozzle.

The pressure applied to the oil or other fuel employed ranges from ten pounds to several hundred pounds per square inch, and as it flows through the tube A, the fitting 2 and the passages 10 and 11, and enters the chamber 9, it will obviously flow from said chamber through the tangentially arranged passages 18 into the central chamber 14, where it will swirl with high velocity before it can discharge through the orifice 15. The higher the velocity the better the atomizing action. However, it is possible to operate with pressures as low as ten pounds and still obtain a good atomizing effect.

In burners of this character, the tip and forward end of the head are subjected to the radiant heat of the furnace into which the flame is projected. As long as there is a full flow of fuel through the atomizing nozzle, danger of choking up is nil, but if the furnace is shut down only momentarily for any reason whatsoever, the oil is liable to carbonize or coke in the passages, and if that happens, it will obviously become necessary to remove the head and the tip C to clean out the several passages.

In most boiler plants, whether on shore or on shipboard, a spare burner tube A and atomizing nozzle are employed, immediately to replace the choked nozzle. Hence the cleaning of the nozzle may be done more or less at leisure, but still all passages should be accessible so that they may be readily cleaned.

After the tube A and the atomizing nozzle as a whole have been removed from the furnace and permitted to cool off, a wrench is placed on the fitting 2, which is hexagonal-shaped, and another on the head B which is also hexagonal-shaped on the exterior. The head may thus be unscrewed from the extension 5 and placed in a vise, and as the head of the atomizing nozzle C is also hexagonal-shaped, it may be unscrewed. As it is unscrewed, it moves away from the pin 19. Thus when it is completely removed, there is a straight longitudinal passage through the nozzle tip which permits ready cleaning, the tangential passages being open from the side to be cleaned. With the tip removed, a drill or scraper may be run down the passages 10 and the passages 11, and thus these are also readily cleaned. After they have been cleaned, the parts may again be re-assembled.

The atomizing nozzle here shown consists of only three parts: the head B, the atomizing nozzle C, and the pin 19. This pin may be permanently secured in the head by running a pin transversely through the head and pin, as indicated at 21. The parts employed are thus reduced to a minimum, and each part is simple to manufacture of machine. Furthermore, all passages are accessible for ready cleaning whenever that is necessary. As the atomizing nozzle is capable of operating under a great range of pressures, and still insures a good atomizing effect, efficiency can be depended upon over a large pressure range.

While the atomizing nozzle has been particularly described in connection with oil burners, it may obviously be used wherever an atomizing effect is desired, as with spray guns, etc.

While this and other features of my invention have been more or less specifically described and illustrated, I wish it understood that various changes may be resorted to within the scope of the appended claims, and that the materials and finish may be such as the experience of the manufacturer and varying conditions of use may demand.

Having thus described and illustrated my invention, what I claim and desire to secure by Letters Patent is—

1. In an atomizing nozzle of the character described, an elongated head member presenting a front and a rear end, a chamber formed in the rear end, means for connecting said chamber

with a source of fluid supply under pressure, a chamber formed in the front end of the head and having an enlarged and a reduced portion, a plurality of passages formed in the head and extending longitudinally of the head, one end of said passages opening through the rear of the head and the other end opening into the enlarged portion of the front chamber, a screw-thread formed in the reduced portion of the front chamber, an atomizing tip having a threaded connection with said screw-thread and closing the front end of the front chamber, a chamber and a discharge orifice formed in the atomizing tip, and a plurality of tangentially arranged inlet passages formed in the atomizing tip, said passages connecting at one end with the enlarged portion of the front chamber and at their opposite ends with the chamber within the atomizing tip.

2. In an atomizing nozzle of the character described, an elongated head member presenting a front and a rear end, a chamber formed in the rear end of the head member, means for connecting said chamber with a source of fluid supply under pressure, a chamber formed in the front end of the head and having an enlarged and a reduced portion, a plurality of passages formed in the head and extending longitudinally of the head, one end of said passages opening through the rear of the head and the other end opening into the enlarged portion of the front chamber, a screw-thread formed in the reduced portion of the front chamber, an atomising tip having a threaded connection with the screw-thread and closing the front end of the front chamber, a longitudinal passage formed in the nozzle tip open at the inner end and terminating in a discharge orifice at the front end, a pin secured in the head and extending into the inner end of the passage formed in the nozzle tip and forming a closure therefor, and a plurality of tangentially disposed inlet passages formed in the nozzle tip, said passages connecting at one end with the enlarged portion of the front chamber in the head and at their opposite ends with the longitudinal passage in the nozzle tip at a point forward of the pin.

3. In an atomizing nozzle of the character described, an elongated head member presenting a front and a rear end, a chamber formed in the rear end, means for connecting said chamber with a source of fluid supply under pressure, a chamber formed in the front end of the head, a plurality of passages extending from a point adjacent the front end of the head and opening through the rear end of the head, an enlarged annular portion formed in the front chamber communicating with the front ends of the plurality of passages, a seat formed at the outer end of the enlarged chamber, a screw-thread formed in the reduced portion of the front chamber, an atomizing tip having a threaded connection with said screw-thread and engaging the seat to close the enlarged chamber, a chamber and a discharge orifice formed within the atomizing tip, and a tangentially disposed passage formed in the atomizing tip communicating at one end with a chamber within the tip and at the opposite end within the enlarged chamber.
